ALBERT CARTER, OF FORRESTVILLE, CONNECTICUT.

Letters Patent No. 79,810, dated July 14, 1868.

IMPROVEMENT IN MACHINES FOR ATTACHING SPANGLES TO HOOPS OF SKIRTS.

The Schedule referred to in these Letters Patent and making part of the same.

TO ALL WHOM IT MAY CONCERN:

Be it known that I, ALBERT CARTER, of Forrestville, in the county of Hartford, and State of Connecticut, have invented, made, and applied to use a certain new and useful Improvement in Conductors for Skirt-Clasp Machines; and I do hereby declare the following to be a full, clear, and exact description of the said invention, reference being had to the annexed drawing, making part of this specification, wherein—

Figure 1 is a view at right angles to the surface of the inclined conductor.

Figure 2 is an elevation edgewise of the inclined conductor, and

Figure 3 is a section at the line $x-x$.

Similar marks of reference denote the same parts.

Machines have heretofore been made that apply the small metal clasps or spangles to hold the tapes to the hoops of skeleton-skirts, said machines inserting the clasp and bending up the teeth, so as to clinch them around the hoops. In machines of this character, the clasps or spangles have been supplied by a conductor that separates the clasps that present themselves correctly from those that are in an improper position for passing into the machine. In consequence of the peculiar shape of these spangles or clasps, it is very difficult to assort and cause them to properly enter the conductor, and frequently those clasps that present themselves in a wrong position at the end of the conductor become wedged, and are difficult to remove by the pliers or wires usually employed for that purpose, and frequently the parts are injured, so that the machines get out of repair. To remedy this difficulty efforts have been made to construct the conductor with a spring side that could be moved by hand, to allow the defective or improperly-placed clasps, or the extraneous matter sometimes found with the clasps, to pass away and free the conductor.

The nature of my said invention consists in a balanced self-acting gate, that is placed in such a relation to the inclined assorting-plate and conductor as to separate the clasps that are properly placed from those that may pass down in a wrong position, and in case of a spangle so presenting itself incorrectly at the gate, said gate is sufficiently raised by the clasp itself to allow the clasp to move further down the incline, and fall away by an opening provided for it, thus causing the gate to be self-acting, and preventing the obstructions heretofore usual in such conductors.

The machine for applying the spangles or clasps to the skirt itself forms no part of my invention, and being known and in use, does not require further description.

The inclined assorting-plate a is to receive the spangles or clasps at its upper end, as usual, and these slide down said plate a in contact with the inclined fence b .

The tendency of the clasps is to lie upon the head with the prongs or points upwards, and in this position the edge of the head slides under the lower edge of the fence b , between that and the assorting-plate a , and the prongs are brought into line by lying against the side of the fence b .

In this position the clasps pass down and alongside of the gate c , that is formed of a wire or rod bent at right angles, and set in eyes, $d d$, to form an axis for the gate to swing on, and c' is the end of the wire or rod that forms a counterpoise that almost balances the gate c .

The clasps slide along between the gate c and fence b , the edges of the heads resting upon the surface of the plate a at the edge of an opening, e , in the plate a , and e is the throat of the conductor, that receives the spangles or clasps in the position shown, so as to pass regularly from there to the machine that applies them to the skirt.

Any clasps that do not become properly placed in sliding down the incline a will either pass outside the end of the gate c and fall into the opening e , or, if they pass in between the gate c and fence b in an incorrect position, the gate c will be raised by said skirt-clasp running under the inclined end of said gate c , and when the clasp reaches the opening e the same will fall away in consequence of being unsupported.

The edge of the hole e is sufficiently removed beneath the fence b to prevent the points of the clasps being supported if said clasps present themselves at an inclination to the surface of the feeding and assorting-plate;

hence the improperly-placed clasps will fall away, while those correctly in position will be supported in consequence of the sides of the heads projecting sufficiently far to prevent their falling into said hole.

What I claim, and desire to secure by Letters Patent, is—

The swinging gate *c* with its end inclined upwards, in combination with the inclined assorting-plate *a*, opening *e*, and fence *b*, substantially as and for the purposes specified.

In witness whereof, I have hereunto set my signature this 29th day of May, A. D. 1868.

ALBERT CARTER.
